UNITED STATES PATENT OFFICE.

HANS SALINGER, OF BERLIN, GERMANY.

DUPLEX METHOD FOR TELEGRAPH CABLES.

Application filed February 8, 1926, Serial No. 86,955, and in Germany February 10, 1925.

Various arrangements are known for effecting duplex operation in telegraph cables or lines, in all of which use is made of the principle that the transmitting current is divided into two equal parts which balance one another in their action upon the receiver.

The invention is diagrammatically illustrated in the accompanying drawings in which Figure 1 represents an artificial cable whilst Figures 2 to 4 are explanatory diagrams.

For carrying the principle above referred to into effect it is necessary to use an artificial line the behaviour of which with respect to the transmitting current is exactly the same as the behaviour of the actual cable or line. According to known methods the transmitting currents may be considered as a superposition of sinusoidal alternating currents and consequently the reproduction of the artificial line need be exact only as regards that range of frequency which corresponds to the frequency of these currents. It is already known to limit this range of frequency in the higher values in such a manner that higher frequencies than are absolutely necessary for telegraphic transmission are omitted, so that as regards these, also the artificial line need no longer correspond. As regards the lower values the range of frequency has not hitherto been limited since for the most usual methods of telegraphic transmission also exceedingly low frequencies and even continuous currents are employed. Consequently hitherto the artificial line has always been so constructed that the cable was balanced also with respect to continuous current (permanent current).

It is true that methods of telegraphy are also known in which the very low frequencies of approximately 1 to 2 periods per second are not utilized (curbing and transmissions according to Delany or over a blocking condenser). Thus for instance Figure 2 shows the curve of the amplitudes of a single sign, viz., of a Morse dot. This curve shows the relative amplitudes of the various frequencies. Only the part of the curve to the left of the dotted line belongs to the required band of frequencies. (See for instance Milnor, Journal A. I. E. E. 41, pages 118-136 of 1922.) Figure 3 shows similarly the curve corresponding to a method of telegraphy in which a single

Morse dot consists of a positive and a negative rectangle as indicated in the figure. It will be seen that the lowermost frequencies have very low amplitudes and that it is permissible to neglect them (approximately on the left of the lefthand dotted line). However, it has not hitherto been recognized that it is the artificial reproduction of the cable for continuous current, which per se appears very simple, that considerably increases the difficulty of balancing, since towards the very low frequencies the properties of the cable are changed considerably. The leakage of the cable depends to a large extent on the frequency, and as regards continuous current it is much smaller than, for instance, for alternating currents of 5 to 10 periods. Moreover, as a rule, as regards the medium frequency of telegraphic transmission the cable has to be considered electrically so long that only its "wave resistance" need be artificially reproduced. On the other hand, as regards the lowest frequencies and permanent current, electrically considered the cable is not long, so that now the important factor is not the "wave resistance", but the "impedance", which in that case is different therefrom. The impedance, however, depends to a very large extent upon the apparatus which are connected at the far end. Therefore, if we retain the lowest frequencies, not only the cable but also the arrangement at the far end has to be artificially reproduced. For all these reasons the retention of the lowest range of frequencies for the artificial reproduction is inconvenient and the reproduction is greatly facilitated if the said range of frequency is dispensed with. The methods to be adopted for this purpose are known. These frequencies are either left out when transmitting, in the manner already above referred to, or they are kept away only from the receiver.

One arrangement for carrying the invention into effect is illustrated by way of example in Figure 1, in which B is the transmitting battery, K_1 and K_2 are the arms of the bridge, L is the cable and N the artificial line. A network of filtering circuits is inserted before the receiver, the object of which filtering circuits is to keep away from the receiver the undesired frequencies. As above stated, this network of filtering circuits may also be arranged in series with the battery B. The artificial line N which has been illustrated in the figure is an arrange-

ment which has proved to be successful in the experiments that have been carried out in connection with a cable having a high inductance. w_1, w_2, w_3, w_4 are ohmic resistances, s_1 and s_2 are self-inductance coils and c_1, c_2, c_3, c_4 and c_5 are condensers. As will be seen this arrangement is not suitable for continuous current, its impedance for low frequencies therefore differs considerably from the impedance of the actual cable.

The difference between a duplex arrangement balanced according to the known method and a duplex arrangement balanced according to the present method will be seen from the curves shown in Figure 4. The ordinates in this figure represent the discrepancy between the artificial cable and the actual cable, and the abscissae the frequency, the scale being the same as in Figures 2 and 3; the full line shows, by way of example, the curve of the discrepancy when the known method is used and the dotted line the curve of the admissible discrepancy for low frequencies.

It is clear that a cable balanced according to the present invention will allow duplex operation to be effected for high speed tele-

raphy, but not for slow Morse operation. However, this is not to be considered to constitute a great disadvantage.

What I claim is:—

1. Duplex method for telegraph cables consisting in balancing the cable only with respect to the range of frequencies required for telegraphy with the exception of the frequencies below two periods per second.

2. Duplex method for telegraph cables consisting in balancing the cable only with respect to the range of frequencies required for telegraphy but not with respect to continuous current and keeping away from the receiver the lowest frequencies for which the cable is not balanced.

3. A method of duplex telegraphy consisting in balancing the cable with respect to the range of frequencies required for telegraphy except with respect to the lowest frequencies, and transmitting the signals by means of currents which do not contain the said lowest frequencies.

In testimony whereof I have signed my name to this specification.

DR. HANS SALINGER.
